UNITED STATES PATENT OFFICE

LYNDON W. JOYCE, OF GREENSBORO, NORTH CAROLINA, ASSIGNOR TO JOYCE-VENNING MANUFACTURING COMPANY, INC., OF GREENSBORO, NORTH CAROLINA, A CORPORATION OF DELAWARE

SUSPENDER ASSEMBLING TOOL

Application filed April 16, 1932. Serial No. 605,753.

This invention relates to the assembling of the suspender slide on the suspender web, and its main object is to provide a simple machine for carrying out the method of assembly disclosed in my Patent No. 1,827,017, granted October 13, 1931, in which the web, prefolded, is placed between the component slide parts, and by pressure of the whole, the slide parts are integrated into a slide with the web folded therebetween.

Another object of the invention is to provide a press for integrating the slide in two steps by means of suitable dies operated by foot or mechanical power, the parts operated upon being allocated by hand with respect to the dies.

A further object of the invention is the provision of dies and the mechanism appurtenant thereto, adapted to be used on any standard press.

Other objects of the invention will appear as the following description of a preferred and practical embodiment thereof proceeds.

In the drawings which accompany and form a part of the following specification, and throughout the several figures of which, the same characters of reference have been used to designate identical parts:

Figure 1 is a side elevation of the press embodying the features of the present invention;

Figure 2 is a front view of the same, parts being shown in section;

Figure 3 is a fragmentary view showing the cams for operating the die plunger;

Figure 4 is a plan view;

Figure 5 is a vertical section taken along the line 5—5 of Figure 4;

Figure 6 is a section taken along the line 6—6 of Figure 5;

Figure 7 is a fragmentary sectional view showing the leading section of the primary die in contact with the slide;

Figure 8 is a perspective view showing the relation of the slide parts and web after the first pressing operation;

Figure 9 is a section taken along the line 9—9 of Figure 4;

Figure 10 is a perspective view showing the relation of the slide parts and web just

prior to the second pressing operation; and

Figure 11 is a fragmentary sectional view showing a modified form of the invention.

Referring now in detail to the several figures the numeral 1 represents in general a press which may be of any suitable or standard construction having a bed plate 2 and an arm 3. The arm supports a casing 4 which may be of any suitable or desired construction, said casing being constructed to serve as a guide for a die plunger or plungers and as a housing for the parts by which said plungers are reciprocated.

In the present embodiment of the invention there are two plungers 5 and 5, the same being normally held in retracted position by means of springs 7 and 8 which at one end, abut a fixed partition 9 in said casing through which the plungers reciprocate, and abutting at the other end against shoulders 10 and 11 formed on end fittings 12 and 13, carrying rollers 14 and 15 which engage the surface of a differential cam 16.

This cam has separate throws which give nonsynchronous movement to said plungers.

The cam 16 is carried by a shaft 17 supported in suitable bearing apertures, to which shaft power is imparted through a belt 18 or its equivalent and the pulley 19. The pulley normally runs free on the shaft 17, but is coupled thereto at will by means of male clutch 20 which engages an annular clutch ring 21 carried by said pulley.

A lever 22 preferably operated by a foot treadle not shown, actuates the clutch element 20.

It is to be understood that the features of construction described up to this point are not necessarily novel and that the identical or equivalent structure may be found in known presses.

Referring now particularly to Figures 4 and 5, a base 23 is detachably secured in any suitable manner to the bed plate 2. Said base comprises a support 24 for a primary fixed die and a support 25 preferably extending at right angles to the support 24, upon which is mounted the secondary fixed die, it being understood that the terms "primary" and "secondary" refer to the sequence

of the two operations performed in the assemblage of the slide with relation to the suspender web. Figure 4 shows that a work plate 26 extends forwardly from the primary 5 fixed die support, the purpose of which is to hold the length of suspending webbing while the first of the assembling operations is being performed.

The slide upon which the device of the 10 present invention operates is of that type comprising a rectangular wire frame 27 and a sheet metal middle bar 28, the latter being folded so as to form a trough and having two sets of teeth, one set 29 extending outwardly and the other set 30 extending inwardly of the sides of the trough. The set 15 of teeth 29 is preferably stamped out of the metal of the trough, leaving apertures, and the set of teeth 30 is designed to register with the apertures.

The work plate 26 is provided with a transverse depression 31 adapted to receive the middle bar in the position shown in Figure 25 6. The depression 31 in the work plate constitutes a part of the primary fixed die, the other part being represented by an anvil 32 adjacent one end of the depression 31, and a small well 33 adjacent the said elevation and outwardly therefrom.

30 The operator places the middle bar of the slide in the depression 31 by hand. In order to facilitate positioning of the same, front and rear guides 34 and 35 are provided, the same being adjustable by means of pin and slot connections so that the width of the space between said guides can be varied to suit the width of the middle bar.

The depression 31 is bounded on the end 40 opposite the anvil by a block 36 on which both of the guides 34 and 35 are mounted, and the block itself is adjustably mounted for movement lengthwise of the depression by means of a pin and slot connection. The pins in each instance are preferably screws which can be tightened down so as to hold the several adjustable parts in fixed relation to the depression. A lateral guide 37 extends along one side of the work plate 26 and is independently adjustable widthwise of said work plate by means of a pin and slot connection, the object of said guide being to engage the side edge of the suspender web and guide it into the trough of the middle bar. Figure 6 shows a portion 38 of the suspender web with the end in position between the sides of the trough of the middle bar awaiting the pressure by means of which the sides of the trough are closed against said web and the set of teeth 30 clampably secured to the end of said web within the middle bar.

60 Since the suspender slides are of various widths, the guide 37 will be adjusted inwardly for a narrow web and outwardly for a web of greater width.

The middle bar, in its initial open or unpressed state is provided with the upwardly extending lugs 39 and 40, one of which lugs sits in the concavity at the top of the anvil 32 when the middle bar is put in place. Prior 70 to the pressing operation, the operator places the frame 27 to the right of the allocated middle bar as shown in Figure 7, with one of the shorter ends hooked over the lug 40. The web having been slipped beneath the guide 34 in the manner shown in Figure 6, and between the sides of the trough 28, the parts are now ready for the first assembling 75 operation.

The primary movable die which does the initial pressing comprises a flat tool 41 having a slot 42 in the lower face adapted to register with the set of teeth 29 so that these teeth will not be mashed in the pressing act. The tool 41 is approximately, as wide as the narrowest slide in connection with which the machine will be employed. In the event that a wider slide is employed, additional width is given to the tool 41 by the auxiliary 80 part 42 similarly slotted at the bottom and being secured to the tool 41 by suitable means such as the screws 43. The tool 41 and the auxiliary part 42, if such be used, are suitably fixed in one of the two relatively slideable parts of a head 59, which head parts are 85 preferably detachably secured to the plungers 5 and 6.

The primary movable die also includes a tool 44 having a downwardly extending guide portion 45 adapted to enter the well 33 and a curved indentation 46 adapted to come down on the free end of the lug 40 and in cooperation with the anvil 32 to bend it tightly around the end portion of the frame 27. The tool 44 is operated by the plunger 6. 100

The timing of the plungers is so determined that the tool 41 comes down first against the middle bar serving as a holding means, and then as it continues its downward movement, pressing the sides of the trough together, the tool 44 descends, curling the end of the lug 40 about the end of the frame 27 in the manner described. As has been stated, the pressing operation just referred to is accomplished by pressure of the 105 operator's foot upon a treadle, clutching the power to the cam shaft 17.

When the cam 16 has rotated so that the plunger rollers 12 and 13 descend from the throws the plungers are elevated, permitting 110 release of the assembled parts, and at this time the operator removes her foot from the treadle declutching the power from the cam shaft so that the plungers remain inactive 115 until another set of parts is in position to be assembled.

When the webbing with the middle bar and frame are removed from beneath the primary movable die, their relation is such as is shown in Figure 8, the middle bar being 120

securely clamped to the end of the web, the set of teeth 29 upstanding, and the frame 27 to one side as shown being clamped beneath the completed lug. The operator then folds 5 the webbing beneath the middle bar and over the top of the middle bar and while it is in this position, she hingedly rotates the frame 27 until its opposite end passes within the lug 39. The parts are now in 10 position for the second or final pressing operation which is performed by means of a secondary set of dies.

Figures 4 and 5 show that the secondary fixed die comprises a block 47 mounted upon 15 the support 25 and having on its top edge an anvil 48 corresponding to the anvil 32 and a well 49 corresponding to the well 33. The block 47 is formed with a bifurcated extension 50 having arms 51 and 52 carrying a 20 stop 53 comprising upper and lower parts 54 and 55, see Figure 9, flanged so as to embrace the outer faces of said arms and held together by a screw or equivalent means 56 passing through the space between said arms. 25 The part 54 is provided on its inner face with a flat channel having a width sufficient to snugly receive the closed lug 40 of the middle bar, when the latter is positioned for the second pressing.

30 The operator takes the web and slide assembled as shown in Figure 10, and thrusts it upon the extension 50 with the extension passing through the loop 57. The open lug 39 is made to rest in the concave end of the 35 anvil 48, the stop 53 having been previously adjusted so that it defines between said anvil and stop, a space having a width just sufficient to receive the slide.

The secondary movable die comprises a 40 member 58 of inverted frusto-pyramidal form and removably attached to the same head 59 to which the primary movable die is attached and which is secured to the plunger 5. The die 58 has on its lower end an 45 extension 60 adapted to enter the well 49 and a curved recess 61 adapted to bear on the upstanding end of the lug 39 and to curl it clampably over the end adjacent bar of the frame 27.

50 The slide with the folded web having been placed upon the block 47 in the manner described, the operator again presses the treadle, bringing the plungers into operation and causing the die 58 to come down 55 upon the lug 39.

It is obvious that two operators can tend this machine, and that the first assembling operation on one web and slide may be performed simultaneously with the second assembling operation on another web and slide.

When the die 58 has receded upwardly, the completed slide with the webbing interfolded in operative position, may be removed from the machine.

55 A simplified form of the invention is con-

templated in which a single primary movable die is employed instead of a die having parts which operate with a differential movement. It is obvious, since the thickness of the webbing and consequently, the amount 70 to which the trough of the middle bar can be closed may vary somewhat, that some means shall be furnished providing a differential pressure between the trough portion of the middle bar and the lug 40. This 75 means as shown in Figure 11, may comprise a depressible table 62 slidably mounted in an aperture in the support 23 and being normally upheld by a stiff spring 63 housed in a counter-bore in said support. The table 80 62 is provided on its upper face with an anvil 64 and a flat part 65 of relatively lower level corresponding to the anvil 32 and well 33. In other words, the table 62 is just a depressible portion of the primary fixed die 85 shown in Figure 5.

Only one plunger and head are required when employing this simplified construction.

When the one-piece primary movable die comes down, it simultaneously closes the 90 trough in the middle bar and closes the lug 40 against the pressure of the spring 63, the table 62 being depressed to compensate for any non-uniformity in the thickness of the trough portion of the middle bar with the 95 web within said trough.

It is obvious from the above description that I have provided simple apparatus for the assembling of the suspender slide and web in such manner as to avoid the necessity of threading the web through a pre-integrated slide following the method of assembling now in common use and that the invention consists not primarily in the press itself for any standard press may be utilized, but in the provision of the especial dies and tool supports for doing the work, and only secondarily in the combination of the tools with a particular type of press. While I have in the above description disclosed what I believe to be a preferred and practical embodiment of the invention, it is to be understood that the details of construction as shown and the arrangement of parts may be varied without transcending the scope of the invention 100 as claimed.

What I claim is:

1. Assembling press for integrating in two stages, a suspender slide of that type having a substantially rectangular frame and a middle bar having a trough and end lugs adapted clampably to embrace the end bars of the frame, and assembling the frame with a suspender web, the latter being folded about the middle bar of the slide to form an adjustable loop, between the two stages of integration, said press including a detachable base having supports, fixed primary and secondary dies carried respectively by said supports, 110 the fixed primary die including means hav- 115

ing an elongated depression forming a seat for the middle bar of the slide and an anvil at one end of said depression provided with a groove in the top forming a seat for the lug 5 at one end of said middle bar; a block mounted on said base forming a wall at the opposite end of said depression, and adjustably slidable to vary the length of said depression, front and rear guides carried by said block and each independently adjustable crosswise of said depression, said front guide being sufficiently elevated from said base to permit a piece of suspender web to be slipped thereunder and into the trough of the slide, 10 an elongated guide disposed forwardly of said depression for engaging the selvage edge of said web, and adjustable lengthwise of the depression for alining said web with the opening in the trough of the middle bar, said base affording support for a frame laid to one side of said anvil and with an end bar thereof within said lug, a head carried by suitable plunger mechanism, and means mounted in 15 said head constituting movable primary and secondary dies registering with the corresponding dies in said base, said movable primary die having a portion pressing said trough together on said web and another portion bending said lug over the said end bar of said frame, said secondary movable die cooperating with the secondary fixed die after the frame and web assembly has been transferred to the latter die for bending the other lug of said middle bar over the opposite end bar of said frame. 20

2. Assembling press as claimed in claim 1, the first portion of said primary die descending independently of and slightly ahead of the said second portion. 25

3. Assembling press as claimed in claim 1, said secondary fixed die being formed with a horn adapted to extend through the adjustable loop of the folded webbing, the upper face of said die including a portion of said horn forming a seat for the slide, and being formed with an anvil for receiving the said other lug of said middle bar, and an adjustable end abutment slidable on said horn, the co-acting face of said secondary movable die corresponding to the second portion of the 30 primary movable die and co-operating with said anvil for the purpose set forth. 45

4. Assembling press for integrating in two stages, a suspender slide of that type having a substantially rectangular frame and a middle bar having a trough and end lugs adapted clampably to embrace the end bars of the frame, and assembling the frame with a suspender web, the latter being folded about the middle bar of the slide to form an adjustable loop, between the two stages of integration, said press including a detachable base having supports, fixed primary and secondary dies carried respectively by said supports, the fixed primary die including means having an elongated depression forming a seat for the middle bar of the slide and an anvil at one end of said depression provided with a groove in the top forming a seat for the lug at one end of said middle bar, a block mounted on said base forming a wall at the opposite end of said depression, and adjustably slidable to vary the length of said depression, front and rear guides carried by said block and each independently adjustable crosswise of said depression, said front guide being sufficiently elevated from said base to permit a piece of suspended web to be slipped thereunder and into the trough of the slide, an elongated guide disposed forwardly of said depression for engaging the selvage edge of 50 55 60 65 70 75 80 85 90 95 100 105 110 115 120 125 130

5 said web, and adjustable lengthwise of the depression for alining said web with the opening in the trough of the middle bar, said base affording support for a frame laid to one side of said anvil and with an end bar thereof within said lug, a head carried by suitable plunger mechanism, and means mounted in said head constituting movable primary and secondary dies registering with the corresponding dies in said base, said movable primary die having a portion pressing said trough together on said web and another portion bending said lug over the said end bar of said frame, said movable die having a 10 slot in its lower face adapted to receive a row of teeth projecting from said middle bar, to avoid these teeth being mashed by said die, said secondary movable die cooperating with the secondary fixed die after the frame and web assembly has been transferred to the latter die for bending the other lug of said middle bar over the opposite end bar of said frame.

15 6. Assembling press for integrating in two stages, a suspender slide of that type having a substantially rectangular frame and a middle bar having a trough and end lugs adapted clampably to embrace the end bars of the frame, and assembling the frame with a suspender web, the latter being folded about the middle bar of the slide to form an adjustable loop, between the two stages of integration, said press including a detachable base having supports, fixed primary and secondary dies carried respectively by said supports, the fixed primary die including a plate secured to said base for receiving the suspender web, having an elongated depression forming a seat for the middle bar of the slide, said base being provided with an anvil at one end of said depression provided with a groove in the top forming a seat at one end of the lug of said middle bar, a plunger operated head, and means mounted in said head constituting movable primary and secondary dies registering with the corresponding dies in said base, said movable primary die having a portion 20 registering with said depression to press said trough together on said web, and another portion registering with said anvil to bend the lug at the adjacent end of said middle bar over the end bar of a frame having one end thereof disposed operatively with respect to said lug, said secondary movable die corresponding with the secondary fixed die after the frame and web assembly has been transferred to the latter die, for bending the other lug of said middle bar over the opposite end bar of said frame.

25 40 7. Assembling press for integrating in two stages, a suspender slide of that type having a substantially rectangular frame and a middle bar having a trough and end lugs adapted clampably to embrace the end bars of the frame, and assembling the frame with a suspender web, the latter being folded about the middle bar of the slide to form an adjustable loop, between the two stages of integration, said press including a detachable base having supports, fixed primary and secondary dies carried respectively by said supports, the fixed primary die including a plate secured to said base for receiving the suspender web, having an elongated depression forming a seat for the middle bar of the slide and an anvil at one end of said depression provided with a groove in the top forming a seat for the lug at one end of said middle bar, a block mounted on said base forming a wall at the opposite end of said depression, and adjustably slidable to vary the length of said depression, front and rear guides carried by said block and each independently adjustable crosswise of said depression, said front guide being sufficiently elevated from said base to permit a piece of suspender web to be slipped thereunder and into the trough of the slide, an elongated guide disposed forwardly of said depression for engaging the selvage edge of said web, and adjustable lengthwise of the depression for alining said web with the opening in the trough of the middle bar, said base affording support for a frame laid to one side of said anvil and with an end bar thereof within said lug, a head carried by suitable plunger mechanism, and means mounted in said head constituting movable primary and secondary dies registering with the corresponding dies in said base, said movable primary die having a portion pressing said trough together on said web and another portion bending said lug over the said end bar of

30 35 40 45 50 55 60 65 70 75 80 85 90 95 100 105 110 115 120 125 130 said frame, the portion of the movable primary die that presses said trough being formed in two parts, one of basic length, and a part attachable thereto aggregating with the basic part the total length of the trough of the middle bar, said secondary movable die cooperating with the secondary fixed die after the frame and web assembly has been transferred to the latter die for bending the other lug of said middle bar over the opposite end bar of said frame.

7. Assembling press for integrating in two stages, a suspender slide of that type having a substantially rectangular frame and a middle bar having a trough and end lugs adapted clampably to embrace the end bars of the frame, and assembling the frame with a suspender web, the latter being folded about the middle bar of the slide to form an adjustable loop, between the two stages of integration, said press including a detachable base having supports, fixed primary and secondary dies carried respectively by said supports, the fixed primary die including a plate secured to said base for receiving the suspender web, having an elongated depression forming a seat for the middle bar of the slide, said base being provided with an anvil at one end of said depression provided with a groove in the top forming a seat at one end of the lug of said middle bar, a plunger operated head, and means mounted in said head constituting movable primary and secondary dies registering with the corresponding dies in said base, said movable primary die having a portion registering with said depression to press said trough together on said web, and another portion registering with said anvil to bend the lug at the adjacent end of said middle bar over the end bar of a frame having one end thereof disposed operatively with respect to said lug, said secondary movable die corresponding with the secondary fixed die after the frame and web assembly has been transferred to the latter die, for bending the other lug of said middle bar over the opposite end bar of said frame.

8. Assembling press for integrating in two stages, a suspender slide of that type having a substantially rectangular frame and a middle bar having a trough and end lugs adapted clampably to embrace the end bars of the frame, and assembling the frame with a suspender web, the latter being folded about the middle bar of the slide to form an adjustable loop, between the two stages of integration, said press including a detachable base having supports, fixed primary and secondary dies carried respectively by said supports, the fixed primary die comprising a plate secured to said base receiving said suspender web and having a depression forming a seat for the middle bar of the slide, said base being provided with anvil at one end of said depression provided with a groove in the top

forming a seat for the lug at one end of said middle bar, a block mounted on said base forming a wall at the opposite end of said depression, and adjustably slidable to vary the 5 length of said depression, front and rear guides carried by said guide and each independently adjustable crosswise of said depression, said front guide being sufficiently elevated from said plate to permit a piece of 10 suspender web to be slipped thereunder and into the trough of said slide, an elongated guide disposed forwardly of said depression for engaging the selvage edge of said web on said plate, and adjustable lengthwise of the 15 depression for alining said web with the opening in the trough of the middle bar, said base affording support for a frame laid to one side of said anvil and with an end bar there- 20 of within said lug, a head carried by said suitable plunger mechanism and means mounted in said head constituting movable primary and secondary dies registering with the corresponding dies in said base, said movable primary die having a portion pressing 25 said trough together on said web, and another portion bending said lug over the said end bar of said frame, said secondary movable die cooperating with said secondary fixed die after the frame and web assembly 30 has been transferred to the latter die for bending the other lug of said middle bar over the opposite end bar of said frame.

9. Assembling press for integrating in two stages, a suspender slide of that type having a substantially rectangular frame and a middle bar having a trough and end lugs adapted clampably to embrace the end bars of the frame, and assembling the frame with a suspender web, the latter being folded about the middle bar of the slide to form an adjustable loop, between the two stages of integration, said press including a detachable base having supports, fixed primary and secondary dies carried respectively by said 35 supports, the fixed primary die including means having an elongated depression forming a seat for the middle bar of the slide and an anvil at one end of said depression provided with a groove in the top forming a seat 40 for the lug at one end of said middle bar, a block mounted on said base forming a wall at the opposite end of said depression, and adjustably slidable to vary the length of said depression, front and rear guides carried by 45 said block and each independently adjustable crosswise of said depression, said front guide being sufficiently elevated from said base to permit a piece of suspender web to be slipped 50 thereunder and into the trough of the slide, an elongated guide disposed forwardly of said depression for engaging the selvage edge of said web, and adjustable lengthwise of the depression for alining said web with the 55 opening in the trough of the middle bar, said base affording support for a frame laid to 60

one side of said anvil and with an end bar thereof within said lug, plungers, means for reciprocating said plungers differentially, a head comprising parts secured to said plungers and independently reciprocated thereby, means mounted in said head constituting movable primary and secondary dies registering with corresponding dies in said base, said movable primary die comprising a portion carried by one part of said head for 70 pressing said trough together on said web, and another portion carried by the other part of said head for bending said lug over the said end bar of said frame, said secondary movable die being carried by the part of 75 the head which carries the first mentioned portion of said primary movable die and co-operating with the secondary fixed die after the frame and web assembly has been transferred to the latter die, for bending the other 80 lug of said middle bar over the opposite end bar of said frame.

10. Assembling press for integrating in two stages, a suspender slide of that type having a substantially rectangular frame and a middle bar having a trough and end lugs adapted 90 clampably to embrace the end bars of the frame, and assembling the frame with a suspender web, the latter being folded about the middle bar of the slide to form an adjustable loop between the two stages of integration, said press including a base, fixed primary and secondary dies on said base, the fixed primary die having a seat for the middle bar 95 and an adjacent seat for the lug at one end of the middle bar, means for adjustably varying both the length and width of the seat for the middle bar, the means for varying the width of said seat for the middle bar being spaced from said base to form a slot through 100 which a piece of suspender web may be slipped, and into the trough of a middle bar positioned in said seat, a head carried by suitable plunger mechanism, and means mounted in said head constituting movable primary 105 and secondary dies registering with the corresponding fixed dies, said movable primary die having a portion pressing said trough together on said web and another portion bending 110 said lug over the said end bar of said frame, said secondary movable die cooperating with the secondary fixed die after the frame and web assembly has been transferred to the latter die, for bending the other lug of 115 said middle bar over the opposite end bar of said frame.

In testimony whereof I affix my signature.
LYNDON W. JOYCE.
